(57) **CLAIM**

The ornamental design for a mobility vehicle, as shown and described.

DESCRIPTION

FIG. 1 is a front, right perspective view of a mobility vehicle showing our new design;

FIG. 2 is a front, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines and the de-emphasized masked portions within depict portions of the mobility vehicle that form no part of the claimed design.
